KEY-LOCKED SLIDABLE BOLT FASTENING
FOR ATTACHE CASES AND THE LIKECharles William Cheney, Hockley,
Birmingham, EnglandApplication October 10, 1946, Serial No. 702,516
In Great Britain March 7, 1944

3 Claims. (Cl. 70—67)

1

The invention relates to a key-locked slidable-bolt fastening member, for an attache case or the like, of the kind having a back plate of shallow oblong form to contain a slidable bolt which is also of shallow oblong form and contains a key-operated tumbler and a key-operated locking plate; the back plate and the bolt being closed by a front plate which is provided on its face with a slidable knob connected through the front plate to the bolt to hand move said bolt against spring pressure. The other fastening member is a hinged hasp having a rigid back loop adapted to pass through an opening in the front plate to be engaged by the nose end of the bolt.

In a slidable-bolt fastening member of the aforesaid kind the invention provides for the key-operated tumbler and the key-operated locking member to be mounted about the same rigid peg of the back-plate projecting through a longitudinal slot in the bolt, and which slot, according to the invention, is provided with a side notch to be engaged by a rigid stump of the locking-plate to hold the bolt from being withdrawn. The locking plate is a revoluble one only upon the peg and oppositely to the stump is formed with a gap to provide two distanced lugs between which the bit of the key operates for rocking said locking plate. The tumbler is a flat and slotted plate and is formed with a forward V edge and with a rear curved edge, and it is arranged to both slide and revolve upon the peg of the back plate, while the stump of the locking plate passes freely through the slotting of the tumbler.

A wire spring, comprising two arms and a coupling coil, is mounted on a stud of the bolt for its one arm to operate against an end of the bolt and its other arm against the forward V edge of the tumbler, this spring being common to bolt, tumbler, and locking plate. The tumbler lies against the inner face of the bolt, and the one arm of the spring lies also against this face and against the V edge of the tumbler, and extending underneath a short arm of the locking plate, which at its ends abuts against the inner face of the bolt and is offset between its ends to accommodate the flat-plate tumbler.

The invention will be clearly understood by the description hereinafter appearing with reference to the accompanying drawings.

Fig. 1 is a front elevation of the slidable-bolt fastening member.

Fig. 2 is an elevation similar to Fig. 1, but with the front plate removed.

2

Fig. 3 is a similar elevation to Fig. 2, but with the locking plate removed.

Fig. 4 shows the back plate, separately.

Fig. 5 shows the slidable bolt, separately.

Fig. 6 shows the tumbler, separately.

Fig. 7 shows the locking plate, separately.

Fig. 8 shows the double arm wire spring, separately.

The back-plate *a*, of shallow oblong-box form *a2*, is provided with a rigid peg *a3* standing upright at about its middle to the depth of the box-form *a2*, other parts of said back-plate, such as *a4* and *a5*, being well known for connection thereto of the front plate *c* of the fastening member, which is of normal construction.

The slidable bolt *d* is of shallow oblong-box form at *d2* and is formed at *d3* with a narrow nose, and is slotted longitudinally at *d4* to engage the peg *a3* of the back plate, and at the one side of it is provided with a bolt-locking notch *d5*, operative as hereinafter explained, said bolt being also formed with a seating *d6* for accommodation of the peg end of a key, with holes *d7* to connect with members of the slidable knob *e*, and with a peg *d8* to anchor the coil *d9* of a double limb spring *f*.

A locking plate *g* has a hole *g2* through it to pivot it upon the peg *a3* of the back plate, and to the one side of said hole a rigid stump *g3* turned inwardly at right angles, while to the other side of said hole *g2*, and oppositely substantially to the stump, is gap *g4* providing two distanced lugs *g5* *g6* between which the bit of the key operates for rocking the locking plate; while further said locking-plate has, adjacent the stump *g3* a projection *g7* under which the one branch of the spring *f* engages to assist in holding the spring in position within the slidable bolt *d*. It will be clear from Fig. 6 that the middle-part of the locking plate is offset at *g8*, to accommodate a tumbler *h*.

The tumbler *h* is flat-plate-like, is slotted at *h2*, and is formed with a forward V edge at *h3*, and at *h4* with a rear and outwardly curved edge, the forward portion of the slotting to accommodate the stump *g3* of the locking-plate *g*, and the rear portion to accommodate the rigid peg *a3* on the back-plate.

It is therefore obvious that the tumbler *h* lies against the inner surface of the slidable bolt, as also do the ends of the locking-plate at each side of the offset, and that both tumbler and plate engage that part of the peg *a3* extending above the slotting, so that the bit of the key can operate upon both tumbler and locking plate, the

former revolving and sliding about the peg, and the latter revolving only about said peg.

The front plate *c* has the usual opening *c*2 across which the bolt nose *d*2 extends, and the knob *e*, having a suitable key-hole *e*2 through it, is connected to the bolt at the riveting points *d*7, so that when the bolt is unlocked the sliding of the knob *e* effects the withdrawal of the bolt against the operation of the spring *f*.

The material parts described and illustrated are relatively arranged with the bolt *d* engaging the box formation of the back-plate and the peg *a*3 of the latter engaging the slot *d*4 of the bolt. The tumbler is positioned within the bolt so that the peg *a*3 engages the rear portion of the slot *h*2, and the locking-plate is applied over the tumbler with its hole *g*2 engaging the peg *a*3 and its stump *g*3 engaging the forward portion of the slot *h*2 of the tumbler; the arrangement being that in the locked positioning of the fastening the stump *g*3 engages the side notch *d*5 in the slot *d*4 of the bolt, the stump *g*3 constantly engaging slot of the tumbler.

The action is as follows: in locking the bit of the key operates the curved rear edge *h*4 of the tumbler to slide the latter forward a short distance against spring action operating against the V edge *h*3, and then immediately picks up the locking-plate *g* to rock same together with the tumbler so that the stump of the locking plate, which projects through the slotting, engages the notch *d*5 of the bolt. In unlocking, the tumbler is first moved to slide it slightly, and afterwards the locking-plate is rocked together with the tumbler to again bring back the stump *g*3 of the locking plate into the straight part *d*4 of the slot in the bolt, when the latter is free to be drawn back against the action of the spring *f*.

The principal features in the construction and arrangement hereinbefore described is that both tumbler and locking plate are mounted upon the same peg of the back plate, the former to slide and revolve, and the latter to revolve only, and that there is a silent wipe-over spring action in locking and unlocking in consequence of a straight limb

of the spring *f* operating against the V edge *h*2 of the tumbler and against one face only of the V, although the action of locking and unlocking can be felt from the key action.

5. What I claim is:

1. A fastenings member of the kind described, wherein both tumbler and locking-plate are mounted about the same rigid peg of the back plate, the tumbler to slide and rock about said peg, and the plate to rock only about said peg, said plate having a locking stump to engage, permanently, the slotting of the tumbler and also adapted to engage a bolt-locking notch at the one side of a longitudinal slot in the bolt, said bolt, tumbler, and locking plate being suitably spring loaded.

2. A fastenings member of the kind described, wherein both tumbler and locking-plate are mounted about the same rigid peg of the back plate, the tumbler to slide and rock about said peg, and the plate to rock only about said peg, said plate having a locking stump to engage, permanently, the slotting of the tumbler and also adapted to engage a bolt-locking notch at the one side of a longitudinal slot in the bolt, said bolt, tumbler, and locking plate being spring loaded by a double armed spring operating between one end of the bolt and an edge of the tumbler.

3. A fastenings member in accordance with the preceding claim, and wherein the tumbler is formed with a forward V edge, and a double armed and coil-coupled wire spring operates between the one end of the bolt and the V edge of the tumbler in manner described.

CHARLES WILLIAM CHENEY.
